FLATWORK IRONER

Bruce E. Maxon, Cincinnati, Ohio

Application March 8, 1947, Serial No. 733,289

9 Claims. (Cl. 38—4)

1

This invention pertains to flat work ironing machines and is particularly directed to improvements in the construction, operation, and arrangement of such machines.

One of the chief objects of this invention is to provide, in a flat work ironing machine, a steam chest of novel form which provides a maximum of ironing surface and at the same time requires a minimum of floor space.

Another object of this invention is to provide in a flat work ironing machine a steam chest of substantially clover-leaf design in which the ironing contact of the work being ironed is made around substantially the entire surface of the steam chest.

A still further object of this invention is to provide a novel design which permits of a maximum reduction in weight of the ironing machine while maintaining a high degree of ironing efficiency.

Another object of this invention is to provide a flat work ironing machine with a series of three rolls triangularly spaced relative to each other, in between which is located a common steam chest operatively engaging all three of said rolls to effect an ironing operation.

It is also an object of this invention to provide a flat work ironing machine with a series of suitably spaced ironing rolls, each engaging a common steam chest of clover-leaf shape in such a manner that the work fed through the machine is in contact with substantially the entire outer surface of the steam chest in effecting an ironing operation.

A further object of this invention is to provide in a multiple roll flat work ironing machine a series of clover-leaf steam chests each having a series of ironing rolls associated therewith and operating simultaneously so as to provide a multiple roll flat work ironer in which the work is in substantially complete contact with the entire ironing surfaces of said steam chests.

And a still further object is to provide in a multiple roll flat work ironing machine having a series of clover-leaf steam chests and a series of ironing rolls associated therewith and operating simultaneously to effect an ironing operation on both sides of the work.

Further features and advantages of this invention will appear from a detailed description of the drawings in which:

Figure I is a diagrammatic perspective view, partly broken away, showing a flat work ironing machine incorporating the novel steam chest mechanism of applicant's invention.

2

Figure II is a diagrammatic showing of an arrangement incorporating applicant's steam chest of Figure I in a machine in which a plurality of steam chest arrangements are interconnected to form a multiple roll high capacity ironing machine.

As an exemplary embodiment of this invention, there is shown, in Figure I, a flat work ironing machine having a frame 1 which supports the steam chest 2 in any suitable manner. This steam chest is formed with a series of concave surfaces 3, 4, and 5 which terminate in convex or lobe portion surfaces 6 so as to form a continuous ironing surface of substantially 10 clover-leaf shape around the entire outside of the steam chest 2.

A series of pressing and feeding rolls 7, 8, and 9 are respectively associated with the concave ironing portions 3, 4, and 5 of the steam chest.

20 These rolls may move to and from the steam chest along the radial lines 10 by suitable journal means and screw down mechanisms of well known character which will not be described in detail as they form no part of this invention. A continuous apron 11 is passed over the periphery of the roll 7 and between this roll and the concave surface 3 of the steam chest, then over the lobe portion 6 between rolls 7 and 8 and between the roll 8 and concave portion 4 of the steam chest. 25 The belt then proceeds over the next lobe portion 6 between the rolls 8 and 9 and over the concave portion surface 5 of the steam chest associated with the roll 9 and then passes partially outwardly under the remaining lobe portion 6 between the rolls 5 and 7 and over an idler roll 12 and then downwardly over a second idler roll 13 at the lower rear portion of the machine frame and then upwardly over a third idler roll 14 back to the roll 7.

30 In this particular embodiment, the rolls 7, 8, and 9 are simultaneously driven, by a suitable motor and power transmission of well known character, in a counterclockwise direction. The work W is initially fed into the machine by the feed ribbons 15 which are driven from the roller 16 and pass over the guide rod 17 so that the work first engages between the roll 7 and steam chest concave surface 3 and passes around over the lobe 6, between rolls 7 and 8, over the concave surface 4 of the steam chest, over the lobe 6 between rolls 8 and 9, and through the concave portion 5 and is finally delivered out by the delivery portion 11d of the apron 11 above the idler roll 12. Thus, in this arrangement, the work 35 is initially fed in from the same side of the ma-

chine to which it is again returned by the delivery apron portion 11d. Suitable drive is provided for rotating the roller 16 in proper timed relationship with the movement of the apron 11 to effect the proper entrance of the work into the ironer.

It will thus be noted that the path traversed by the work is in continuous contact with the steam chest from the time the work contacts the chest at the point 18 until it emerges from contact with the steam chest at the point 19 to thus provide a maximum of ironing surface while at the same time having a steam chest of small overall dimensions, light-weight, and space-saving character. In this arrangement of steam chest and ironing rolls, it is apparent that substantially no portion of the steam chest is exposed and unused for ironing with the result that heat loss is minimized. Only a small portion of the lobe 6 between rolls 7 and 9 is exposed in nonironing relationship to the apron and work being driven through the machine. Thus, not only is weight and space saved, but also the substantially complete insulation of the steam chest by the work and apron around its periphery is thereby obtained. It will also be noted that the actual pressing of the work piece by the rolls 7, 8, and 9 is effective on more than half of the steam chest surface, the concave ironing portions 3, 4, and 5 forming at least half the peripheral area of the clover-leaf shaped steam chest 2.

This invention is also well adapted to a machine wherein there is a plurality of clover-leaf shaped steam chests each having a plurality of rolls in ironing engagement therewith. Referring particularly to Figure II, there is noted an exemplary arrangement wherein two steam chests 2a and 2b, similar to the chest 2 in Figure I, are utilized. In this particular arrangement, these chests 2a and 2b are carried on an appropriate frame 1a of usual structure and which will not be described in detail as this arrangement is well known and forms no specific part of applicant's present invention. Associated with the steam chest 2a are the pressure rolls 7a, 8a, and 9a, each of which are positioned in the concave areas 3a, 4a, and 5a of the steam chest 2a. In this arrangement, the three rolls 7a, 8a, and 9a are rotated together by appropriate means in a counterclockwise direction. The work is placed on the feed ribbons 15a which are driven from a suitable roll 16a and guided by the rod 17a so that the work enters at the point 18a. The apron 11a, passing over the roll 7a, carries the work W through the arcuate portion 3a where the roll 7a effects ironing action, around over the lobe portion 6a of the chest 2a, to the roll 8a and through the concave portion 4a, around over the lobe portion 6a between the rolls 8a and 9a. The work is conducted then through the concave portion 5a by the roll 9a to emerge from the first steam chest 2a at the point 19a. The apron 11a continues on around over the roll 9a and is guided by the idler roll 13a. The apron 11a then is guided by the roll 7b, associated with the second steam chest 2b, then over an idler pulley 13c, back over the idler roll 14a, back to the roll 7a to complete its circuit.

As the work emerges from the point 19a associated with the steam chest 2a, it is picked up between the apron 11a and the apron 11b which is guided over the idler roll 12a and by the roll 9a, during which time the work is held between both the aprons 11a and 11b as these aprons and the work pass over the idler roll 13a up to the

roll 7b of the second steam chest 2b. In this way, the work is transferred to the second series of ironing rolls, for ironing the other side of the work from that ironed by steam chest 2a, the work entering the second series at the point 18b and continuing on through the concave portion 3b of the chest 2b, over the lobe portion 6b between the rolls 7b and 8b. It then proceeds through the concave portion 4b, over the lobe portion 6b between the roll 8b and the final roll 9b. After the work passes through the concave portion 5b, associated with the roll 9b, it is conducted down to the delivery apron 20 from which the finished work is removed from the machine. The apron 11b continues on downwardly over the guide roll 21 and the guide roll 22 and finally over the guide roll 23 back to the initial entrance roll 12a.

It will be noted that the rolls related to the second steam chest 2b are rotated in a clockwise or opposite direction from that of the rolls in the first series of ironing rolls associated with the steam chest 2a. It is also to be noted that by the utilization of a plurality of the steam chest arrangements, a very compact machine capable of ironing both sides of the work is provided which is both light in weight and has a maximum of ironing surfaces 3a, 4a, and 5a; and 3b, 4b, and 5b closely coupled together in a compact machine structure. Thus, the distance between the feed ribbons 15a and the final discharge or delivery apron 20 is minimized while maintaining a maximum of ironing area in the machine. This greatly facilitates the installation in an efficient manner of the machine with a minimum of floor space consumption.

While the apparatus herein disclosed and described constitutes a preferred form of the invention, it is to be understood that the apparatus is capable of mechanical alteration without departing from the spirit of the invention and that such mechanical arrangements and commercial adaptations as fall within the scope of the appended claims are intended to be included herein.

Having thus fully set forth and described this invention, what is claimed as new and desired to be secured by United States Letters Patent is:

1. In a flat work ironing machine, a steam chest, three concave ironing surfaces of substantially the same size and shape and equi-angularly spaced apart on said steam chest, three ironing pressure rolls, each of said rolls being operatively associated with one of said concave ironing surfaces, and lobe portions on said steam chest with one lobe portion projecting between each pair of said rolls.

2. In a flat work ironing machine, a steam chest, three concave ironing surfaces of substantially the same size and shape and equi-angularly spaced apart on said steam chest, three ironing pressure rolls, each of said rolls being operatively associated with one of said concave ironing surfaces, lobe portions on said steam chest with one lobe portion projecting between each pair of said rolls, and a feed apron driven by said rolls passing over said concave ironing portions and said lobe portions.

3. In a flat work ironing machine, a steam chest, three concave ironing surfaces of substantially the same size and shape and equi-angularly spaced apart on said steam chest, three ironing pressure rolls, each of said rolls being operatively associated with one of said concave ironing surfaces, lobe portions on said steam chest with one lobe portion projecting between each pair of said

rolls, a feeding apron driven by said rolls passing over said concave ironing portions and said lobe portions in uninterrupted contact with substantially all of the outside surface of said steam chest, and means for initially presenting the work to be ironed between one of said rolls and its associated concave ironing surface on the steam chest.

4. In combination in a flat work ironing machine, a steam chest having a substantially clover-leaf cross-section comprising a series of concave ironing surfaces and convex lobe portions merging in a continuous surface of continuity around said steam chest, a series of pressing rolls operatively associated with said concave surfaces, an apron guided by said rolls over said concave surfaces and convex lobe portions of said steam chest, and means for entering and removing work from between said apron and said steam chest at the same lobe portion of said steam chest.

5. In a flat work ironing machine, a steam chest, a plurality of concave ironing surfaces about said chest uniformly distributed about its periphery, a plurality of pressing rolls arranged about said chest and extending into said ironing surfaces, lobe portions on said steam chest, each of said lobe portions projecting between a pair of said rolls, an endless apron extending between said rolls and chest and passing over said lobes and of substantially greater length than the periphery of said chest, idler rolls receiving and supporting said apron where it leaves the pressing rolls on opposite sides of one of said lobes thereby exposing the said one lobe, and means for feeding work through said ironing machine by initially charging said work between the apron and the said one lobe and receiving said work from between the apron and the same said one lobe so as to provide substantially complete contact of the work to be ironed around the entire surface of said steam chest.

6. In combination in a flat work ironing machine, a steam chest, a series of pressure rollers arranged at the apices of an equilateral triangle about said steam chest, and lobe portions on said steam chest extending between each pair of said rolls, and a work carrying apron driven by said rolls and contacting all of the peripheral surface of said steam chest except the outermost part of one of said lobes.

7. In an ironing machine, the combination of a steam chest having three uniformly peripheral spaced convex lobe portions interconnected by concave ironing surfaces, three rolls uniformly spaced from each other about said steam chest and operatively associated with said concave ironing surfaces, and a work conducting apron extending about said chest under said rolls to be driven by the rotation of said rolls and engaging all of said concave surfaces and two of said lobes while leaving substantially all of the remaining lobe of said steam chest exposed for the entry and exit of articles to be pressed to and from between said apron and chest.

8. In combination in a flat work ironing machine, a pair of adjacent steam chests each having a substantially clover-leaf configuration in cross-section comprising a series of concave ironing surfaces and convex lobe portions therebe-

tween merging into a continuous surface of continuity around said steam chest, said ironing surfaces and said lobe portions being substantially equi-angularly spaced around their respective chests, a series of pressing rolls operatively associated with said concave surfaces, an apron for each chest passing between the rolls thereof and the said ironing surfaces and over the convex lobe portions of the said chests, means for introducing work to be ironed between the apron and one side of one of the lobes of one of said steam chests, means for removing the work from between the apron and the other side of the same lobe, and means for conveying the work removed from the one chest to the other chest and for inserting it between the apron of the said other chest and one side of one of the said lobe portions thereof, said means including idler rolls supporting the aprons of said chests so they run contiguously between the discharge point of the said one chest and the work receiving point of the said other chest.

9. In combination in a flat work ironing machine, a pair of adjacent steam chests each having a substantially clover-leaf configuration in cross-section comprising a series of concave ironing surfaces and convex lobe portions therebetween merging into a continuous surface of continuity around said steam chest, said ironing surfaces and said lobe portions being substantially equi-angularly spaced around their respective chests, a series of pressing rolls operatively associated with said concave surfaces, an apron for each chest passing between the rolls thereof and the said ironing surfaces and over the convex lobe portions of the said chests, means for introducing work to be ironed between the apron and one side of one of the lobes of one of said steam chests, means for removing the work from between the apron and the other side of the same lobe, and means for conveying the work removed from the one chest to the other chest and for inserting it between the apron of the said other chest and one side of one of the said lobe portions thereof, said means including idler rolls supporting the aprons of said chests so they run contiguously between the discharge point of the said one chest and the work receiving point of the said other chest, said aprons being so arranged that opposite sides of the work are pressed on alternate of the said chests whereby the work is ironed on both sides.
